UNITED STATES PATENT OFFICE.

ALVIN H. SCHAALE, OF BUTTE, MONTANA.

SHOCK-ABSORBER.

1,099,943.

Specification of Letters Patent. Patented June 16, 1914.

Application filed August 12, 1913. Serial No. 784,374.

To all whom it may concern:

Be it known that I, ALVIN H. SCHAALE, a citizen of the United States, residing at Butte, in the county of Silverbow, State of Montana, have invented certain new and useful Improvements in Shock-Absorbers; and I do hereby declare the following to be a full, clear, and exact description of the invention, such as will enable others skilled in the art to which it appertains to make and use the same.

This invention relates to shock absorbers and has for an object to provide a device of this character including an elliptical spring operatively connected to a piston and its casing with means for locking the piston stationary should the spring become broken.

A further object is to provide a device of this character that will be formed of a few simple and inexpensive parts which will not easily get out of order.

With the above objects in view the invention consists of certain novel details of construction and combination of parts herein-after fully described and claimed, it being understood that various modifications may be made in the minor details of construction within the scope of the appended claims.

In the accompanying drawing illustrating this invention:—Figure 1 is a side elevation showing the application of my invention to a wheel hub. Fig. 2 is a rear elevation. Fig. 3 is a longitudinal sectional view taken on the line 3—3 Fig. 1. Fig. 4 is a fragmentary sectional view taken on the line 4—4 Fig. 2.

Referring now to the drawing in which like characters of reference designate similar parts, 10 designates the hub of a wheel, 40 and 11 the spindle thereof.

In carrying out my invention I provide an eye 12 for engagement with the spindle, the eye terminating at the upper end in a transversely disposed integral U-shaped clip 13 which receives the lower side of an elliptical spring 14. There is a U-shaped clip 15 disposed to engage the upper side of the elliptical spring in the same manner as the lower clip 13. A cylindrical piston casing 16 is engaged through the legs of the upper clip, there being a shoulder 17 on the casing which bears upon the upper side of the clip, and there being a nut 18 threaded on to the lower end of the casing and engaged against the lower side of the clip to secure the casing to the clip.

A piston 19 in the nature of a cylindrical rod is slidably and frictionally disposed in the bore of the casing 16 and passes down outside of the elliptical spring 14 as shown, 60 the piston being terminally passed through the legs of the lower clip 13. There is a shoulder 20 formed on the piston to bear against the upper side of the lower clip, and a nut 21 is threaded on the piston and bears 65 against the lower side of the lower clip, whereby the piston is secured firmly to the lower clip. It will thus be observed that upon vibration of the elliptical spring, the piston will reciprocate within the casing, the 70 frictional engagement of the piston in the casing being the agency to absorb shocks.

For locking the piston stationary to the casing in case of breaking of the elliptical spring, there is an eye 22 formed on the collar 17 of the casing, and a set screw 23 is threaded through this eye and through an opening 24 in the casing, and is adapted to be advanced into engagement with the piston when it is desired to lock the piston stationary to the casing. When the piston is locked to the casing, it is evident that there is a single rigid connection between the wheel spindle and casing.

From the above description it will be seen 85 that I have provided an extremely simple and inexpensive shock absorber of the class described which is formed of a few simple and durable parts that will not easily get out of order, and which will operate effectively under various conditions of service.

What is claimed, is:—

1. A shock absorber including an elliptical spring, a clip secured to the lower side of the spring, a second clip secured to the 95 upper side of the spring, a piston casing secured to the upper clip, a piston in said casing secured to the lower clip, and a set screw for locking the piston stationary to the casing.

2. A shock absorber including an elliptical spring, a clip secured to the lower side of the spring, a second clip secured to the upper side of the spring, a piston casing secured to the upper clip, a piston in said casing secured to the lower clip, and a set screw threaded into said casing and adapted to be engaged with said piston for locking the piston stationary to the casing.

3. A shock absorber including an elliptical spring, a wheel engaging member having a clip at the upper end engaging the

lower side of said elliptical spring, a clip secured to the upper side of said elliptical spring, a piston casing secured to the upper clip, a piston in said casing secured to the lower clip, and a set screw for locking said piston stationary to said casing.

4. A shock absorber including a wheel attaching eye having at the top a laterally extending substantially U-shaped clip, an elliptical spring having the lower side engaged in said clip, a second U-shaped clip engaging the upper side of said spring, a casing removably secured at the lower end

to the upper clip, a piston in said casing removably secured at the lower end to the lower clip, and a set screw threaded in said casing and adapted to be engaged with said piston for locking said piston stationary to said casing.

In testimony whereof, I affix my signature, in the presence of two witnesses.

ALVIN H. SCHAAAL.
